UNITED STATES PATENT OFFICE.

CARL W. A. KOELKEBECK, OF PITTSBURG, PENNSYLVANIA.

DESIGN FOR A HYDRAULIC-VALVE CASING.

SPECIFICATION forming part of Design No. 34,035, dated February 5, 1901.

Application filed December 6, 1900. Serial No. 38,970. Term of patent 7 years.

To all whom it may concern:

Be it known that I, CARL W. A. KOELKEBECK, a citizen of the United States, residing at Pittsburg, in the county of Allegheny, State of Pennsylvania, have invented and produced a new and original Design for a Hydraulic-Valve Casing, of which the following is a specification, reference being had to the accompanying drawings, forming part thereof.

Figure 1 is a side elevational view of a hydraulic-valve casing, showing my new design; and Fig. 2, a front view of the same.

My design consists of a valve-casing as shown by the drawings, and the leading features of my design comprise the cylindrical central portion and the parts or branches extending therefrom.

Referring to the drawings, the casing comprises the vertical cylindrical body portion 1, made hollow throughout its length for the reception of certain parts of a valve. A number of cylindrical branches or parts extend outwardly from the body portion and are designed for passages or nozzles—that is to say, the part or branch 2 is for the main supply passage or nozzle and the branch 3 for the main exhaust-passage. These branches are parallel to each other and both parallel to the body portion. The other cylindrical branches

or parts 4, 4^a, and 5 are designed for the machine-passages and a by-passage, respectively. The casing is also provided with the parts 6 and 7, located on opposite sides of the body portion.

The essential features of my design consist of a casing for a single-bore hydraulic valve comprising a cylindrical body portion having parts or branches extending outwardly therefrom and designed for supply, machine, exhaust, and by-passages or nozzles, the branches designed for the supply and exhaust passages or nozzles being parallel to the cylindrical body portion and the axes of all the branches or parts designed for the passages or nozzles being in the same plane.

Having thus described my invention, what I claim as new, and desire to secure by Letters Patent, is—

The design for a hydraulic-valve casing as herein shown and described.

In testimony whereof I have signed my name to this specification in the presence of two subscribing witnesses.

CARL W. A. KOELKEBECK.
